UNITED STATES PATENT OFFICE.

WILLIAM SUNDBERG, OF CHICAGO, ILLINOIS; ELIZABETH L. SUNDBERG ADMINISTRATRIX OF SAID WILLIAM SUNDBERG, DECEASED.

GRAIN-DOOR-REMOVING DEVICE.

Application filed June 11, 1920. Serial No. 388,296.

To all whom it may concern:

Be it known that I, WILLIAM SUNDBERG, a citizen of the United States, and a resident of Chicago, county of Cook, and State 5 of Illinois, have invented a certain new and useful Grain-Door-Removing Device, of which the following is a specification.

My invention relates to improvements in means for removing the inner, or grain door from a box car, said door being commonly fastened at the sides and on the inside of a box car as by means of nails. When the term "grain doors" is used in this specification it refers to the inner door of a box car, 10 whether the car be loaded with grain, coal or any other material which is shipped in bulk form in box cars.

By the means now in general use for removing grain doors, a sledge or hammer is 20 used to knock the grain door loose. This not only takes considerable time, but also considerably damages the grain door so that it must be repaired before it can be used again.

The objects of my invention are, first, to 25 provide a means for quickly removing a grain door from a box car; second, to provide a means for quickly removing a grain door from a box car as by mechanical means and without materially damaging the said 30 grain door; third, to provide a means for removing grain doors which can be used in conjunction with, or without, the unloading machine which is described in my application, Serial Number 331,561, filed October 35 18, 1919.

This device, while being shown in the accompanying drawings as being attached to the before mentioned unloading machine, can of course, be used independently, that is 40 to say, this device can be used as a separate and distinct device for removing grain doors.

One form of my invention is shown in the drawings, in which Fig. 1 is a side elevation 45 of the door removing device, it being shown as attached to the unloading machine, a general outline of the unloading machine also being shown.

Fig. 2 is a front elevational view of one 50 of the pry-off members.

Fig. 3 is a plan view taken substantially on line 3—3 of Fig. 1, a general outline of the unloading machine also being shown.

Referring to the drawings, the side frame

castings 45 and 46, shafts 99, 104 and 105, 55 and angle 50 are all part of the unloading machine as described in my said application, Serial Number 331,561.

The door removing device consists of the following parts: two pry-off members, 1 and 60 2, each of which is composed of two channels, said channels being separated as by means of a plurality of plates, 3, and being fastened together as by means of bolts or rivets. Attached to and extending out from 65 each of the pry-off members 1 and 2, are a plurality of sharpened pins, 8.

Links 4 and 5 are each pivotally mounted at one end on shaft 105, and at the other end are pivotally mounted on pins 6 and 7 carried by the respective pry-off members 1 and 2, said last mentioned end of the links 4 and 5, respectively, being placed between the two channels of which the pry-off members 1 and 2 are composed, the pins 6 and 7, respectively, passing through each pair of channels as shown and being held in place as by means of cotter pins. 70

Bell crank levers 9 and 10 are each pivotally connected at one end to pry-off members 1 and 2, respectively, as by means of pins 11 and 12, said pins passing through each pair of channels and being held in place as by means of cotter pins. Shaft 104, on 80 which levers 9 and 10 are mounted, serves as a fulcrum for the said levers. Collars 13, 14, 15 and 16 serve to hold links 4 and 5, and levers 9 and 10, respectively, in place on shafts 105 and 104, said shafts extending out from castings 45 and 46 far enough to 85 accommodate said collars, links and levers. 90

Sheaves 17 and 18 are attached to angle 50 as shown, said angle extending out from frame castings 45 and 46 far enough to accommodate said sheaves. 95

Loosely mounted on shaft 99 are drums 19 and 20, each of which is fitted with a friction clutch 21 and 22, respectively. A rope, or cable, 23, one end of which is fastened to drum 19, passes over sheave 17 and 100 has its other end fastened to the upper end of lever 9. A similar rope, 24, connects drum 20 to lever 10.

The operation of the door removing device is as follows: The operator brings the 105 unloading machine to the front of the door, 25, which is to be removed from the car 40. Then he throws clutches 21 and 22 in, thus

causing ropes 23 and 24 to wind up on drums 19 and 20, respectively, and causing levers 9 and 10, links 4 and 5, pry-off members 1 and 2, and door 25 to take the position shown by dotted lines, the grain door 25 thus being pried loose.

The pins, 8, grip the door, 25, and hold same. When the pry-off members are in the position shown by dotted lines, the operator 10 throws clutches 21 and 22 out, the pawls 34 and 35, which engage the ratchet faced flanges of drums 19 and 20, respectively, preventing the pry-off members, against which door 25 is held, from dropping.

15 The grain or other material with which the car is loaded is thus permitted to flow out of the car from the sides and under the door. When the grain which is in front of the door has flowed out of the car by gravity, 20 the operator lifts the pawls 34 and 35, thus allowing pry-off members 1 and 2 to drop to the position shown by full lines and jarring door 25 loose from the said pry-off members. The operator next removes the 25 door from the car and the remainder of the contents of the car may be removed by any desired means, for example, by the unloading machine described in my said application, Serial Number 331,561.

30 Links 4 and 5, which rest upon the upper angular face of lugs 28 and 29, said lugs being part of castings 45 and 46, respectively, prevent pry-off members 1 and 2 from dropping below the position shown by full lines. Pry-off members 1 and 2 are prevented from falling backward towards the machine when in the position shown by full lines, because of lugs 36 and 37, said lugs projecting out from and being part of castings 45 and 46, respectively, the pry-off members resting against said lugs.

To prevent the unloading machine from backing up when pressure is applied to the grain door 25, pawls 30 and 31 are provided, 45 said pawls being placed between castings 45 and 46, respectively, and being mounted on pins 32 and 33, respectively, said pins passing through castings 45 and 46, respectively, and being held in place as by means of cotter pins. Notches are cut in rails 318 and 319, pawls 30 and 31 engaging these notches and preventing the machine from backing up. When pawls 30 and 31 are not in use they can be held in the position shown by dotted lines by catch members 26 and 27 adapted to hook over castings 45 and 46, respectively, as shown.

Inasmuch as this disclosure will suggest to others, various modified structures and 60 mechanisms whereby the substantial objects and purposes of my invention may be attained, I do not wish to be limited to the exact construction shown and described.

I claim as my invention.

65 1. A device for removing grain doors

from box cars comprising a supporting frame adapted to be positioned adjacent the grain door, a pry-off member adapted to be positioned against the grain door, a lever pivotally connecting said member to said frame, a drum journaled on said frame, means to rotate said drum, and flexible means attached at one end to said drum and at the other end to said lever.

2. A device for removing grain doors 75 from box cars comprising a supporting frame adapted to be positioned adjacent the grain door, a vertically disposed pry-off member adapted to be positioned adjacent to and having means adapted to bite into 80 the grain door, a bell crank pivotally carried by said frame and having one arm pivotally connected to said pry-off member, a drum journaled on said frame, means to rotate said drum and flexible means attached 85 at one end to said drum and at the other end to the other arm of said bell crank.

3. A device for removing grain doors 90 from box cars comprising a supporting frame adapted to be positioned adjacent the grain door, a vertically disposed pry-off member adapted to be positioned adjacent to and having means adapted to bite into 95 the grain door, a bell crank pivotally carried by said frame and having one arm pivotally connected to said pry-off member, a drum journaled on said frame, means to rotate said drum, flexible means attached at one end to said drum and at the other end to the other arm of said bell crank, and 100 means to limit vertical movement of said pry-off member.

4. A device for removing grain doors from box cars comprising a supporting frame 105 adapted to be positioned adjacent the grain door, a vertically disposed pry-off member adapted to be positioned adjacent to and having means adapted to bite into the grain door, a bell crank pivotally carried by said frame and having one arm pivotally connected to said pry-off member, a drum journaled on said frame, means to rotate said 110 drum, flexible means attached at one end to said drum and at the other end to the other arm of said bell crank, and means to 115 prevent backward rotative movement of said drum, for the purpose specified.

5. A device for removing grain doors from box cars comprising a supporting frame adapted to be positioned adjacent the grain door, a vertically disposed pry-off member adapted to be positioned adjacent to and having means adapted to bite into 120 the grain door, a bell crank pivotally carried by said frame and having one arm pivotally connected to said pry-off member, a link pivotally connected to said frame and member and operating substantially parallelly to said bell crank arm, a drum journaled on said frame, means to rotate said 125 130

drum, and flexible means attached at one end to said drum and at the other end to the other arm of said bell crank.

6. A device for removing grain doors from box cars comprising a supporting frame adapted to be positioned adjacent the grain door, a vertically disposed pry-off member adapted to be positioned adjacent to and having means adapted to bite into the grain door, a bell crank pivotally carried by said frame and having one arm pivotally connected to said pry-off member, and power means connected to the other arm of said bell crank, for the purpose specified.

15 7. A device for removing grain doors from box cars comprising a supporting frame adapted to be positioned adjacent the grain door, a vertically disposed pry-off member adapted to be positioned adjacent to and having means adapted to bite into the grain door, a bell crank pivotally carried by said frame and having one arm pivotally connected to said pry-off member, a link pivotally connected to said frame and member 20 and operating substantially parallelly to said bell crank arm, and power means connected to the other arm of said bell crank, for the purpose specified.

8. A device for removing grain doors from box cars comprising a supporting frame adapted to be positioned adjacent the grain door, a plurality of vertically disposed pry-off members adapted to be positioned ad-

jacent to and having means adapted to bite into the grain door, a plurality of bell cranks 35 pivotally carried by said frame, one arm of each bell crank being pivotally connected to the adjacent pry-off member, links pivotally connected to said frame and respective pry-off members and operating substantially 40 parallelly to said respective bell crank arms, and power means connected to the other arms of said bell cranks, for the purpose specified.

9. A device for removing grain doors from box cars comprising a supporting frame adapted to be positioned adjacent the grain door, a plurality of vertically disposed pry-off members adapted to be positioned adjacent to and having means adapted to bite 45 into the grain door, a plurality of bell cranks pivotally carried by said frame, one arm of each bell crank being pivotally connected to the adjacent pry-off member, links pivotally connected to said frame and respective 50 pry-off members and operating substantially parallelly to said respective bell crank arms, drums journaled on said frame, means to rotate said drums, and flexible members attached at one end to said respective drums 55 and at the other end to the other arms of said respective bell cranks.

In testimony whereof, I have hereunto set my hand this 8th day of June, 1920.

WILLIAM SUNDBERG.
